UNITED STATES PATENT OFFICE.

JOHN A. METHOT, OF WORCESTER, MASSACHUSETTS, ASSIGNOR TO BENJAMIN JOSEPHS
AND JULIUS H. CORASH, BOTH OF WORCESTER, MASSACHUSETTS.

DESIGN FOR A SMALL HAND BAG.

Application filed October 25, 1926. Serial No. 19,475. Term of patent $3\frac{1}{2}$ years.

To all whom it may concern:

Be it known that I, JOHN A. METHOT, a citizen of the United States, residing at Worcester, in the county of Worcester and State of Massachusetts, have invented a new, original, and ornamental Design for Small Hand Bag, of which the following is a specification, reference being had to the accompanying drawing, forming part thereof.

The figure is a perspective view of a hand bag showing my new design.

I claim:

The ornamental design for a small hand bag as shown.

JOHN A. METHOT.
